HEAVY DUTY LIQUID SYNTHETIC
DETERGENT COMPOSITION

Lawrence Dasch and Paul R. Cutter, Painesville, Ohio,
assignors to Diamond Alkali Company, Cleveland,
Ohio, a corporation of Delaware
No Drawing. Filed Feb. 10, 1958, Ser. No. 714,013
11 Claims. (Cl. 252—137)

This invention relates to synthetic heavy-duty liquid detergents, and more particularly to synthetic heavy-duty liquid detergent compositions wherein the principal building and sequestering agent is sodium tripolyphosphate.

In recent years, the natural detergents, such as the various soaps, have been replaced to a considerable extent by synthetic detergents, particularly in the laundry field, both home and commercial. This has come about primarily because the synthetic detergents, unlike the natural detergents are resistant to both acids and hard water. Thus, synthetic detergents can be used both in cleaning processes where the pH is below 8, in which processes the soaps dissociate and can not be used, as well as in hard water wherein the soaps form insoluble calcium and magnesium compounds, which compounds are deleterious to the cleaning action of the soap.

The synthetic detergents have, for the most part, been marketed in the form of a powder, which powder is generally made up of an anionic detergent, such as a sodium alkyl aryl sulfonate, a foam stabilizer, such as a condensed alkanolamide of a fatty acid, a building or sequestering agent, such as sodium tripolyphosphate or tetrasodium pyrophosphate, a rust or corrosion inhibitor, such as sodium metasilicate, a soil suspending agent, such as sodium carboxy methyl cellulose and minor amounts of an optical bleach and a dye. These ingredients make up about 70% of the composition, the remaining 30% being an inert electrolyte, such as sodium sulfate, which although added mainly to increase the bulk of the finished detergent product, does itself have some detergent value.

More recently, synthetic heavy-duty detergents in liquid form have begun to be preferred over the powders. The liquids have been found to be more convenient to use, i.e., they can be easily poured from their containers and resealed therein by means of a replaceable cap, while the powders have a tendency to spill out of their cartons. Moreover, the liquids are instantly soluble in either hot or cold water, while powders, in a laundering operation, may fold into the dry clothes and not get completely into solution until the wash cycle is half over. However, since these detergent compositions are in solution rather than in the dry state, a radical change in their formulation over that of the dry powder formulation has been necessary.

The primary departure in a liquid heavy-duty synthetic detergent formulation from that of a dry formulation is the use of a potassium polyphosphate as the alkaline builder or sequestering agent instead of a sodium polyphosphate. This change is necessary because of the limited solubility of the sodium polyphosphates in water, hence making it impossible to incorporate the necessary amount of detergent composition and builder or sequestering agent in the solution without causing it to break up into a solid-liquid phase. In addition, it is necessary to incorporate a solubilizing agent such as sodium xylene sulfonate into the composition, which agent aids in dispersing the organic detergent constituents in the solution. Finally, the sodium sulfate filler used in the powder is replaced in the liquid detergent by water.

2

Although such a liquid composition, utilizing a potassium polyphosphate as the building agent or sequestering agent, gives cleaning results comparable to those obtained by using a heavy-duty detergent powder, such a composition does have several disadvantages. Foremost, is the fact that the potassium polyphosphates are about twice as expensive as the corresponding sodium polyphosphate, thus causing a considerable increase in price of such a liquid heavy-duty detergent over that of the corresponding powder. In addition, the building and sequestering action, on an equal weight basis, of the potassium polyphosphates are somewhat less than those of the corresponding sodium polyphosphates, hence making it necessary to use a greater amount of the potassium polyphosphates to achieve results comparable to those achieved when using the sodium polyphosphates.

It is, therefore, an object of this invention to provide a synthetic heavy-duty liquid detergent composition, which composition utilizes sodium tripolyphosphate as the principal building or sequestering agent.

A further object of this invention is to provide a synthetic heavy-duty liquid detergent of the above composition, which detergent is equal in cleaning performance to both the heavy-duty detergent powders and the heavy-duty liquid detergents which use a potassium polyphosphate as the building or sequestering agent.

These and other objects will become apparent to those skilled in the art from the description of the invention which follows.

Pursuant to the above objects, it has been found that by incorporating a small amount of a water-soluble lithium compound into the heavy-duty liquid detergent formulation, a heavy-duty liquid detergent composition can be made utilizing sodium tripolyphosphate as the major building or sequestering agent, and which composition is equal in cleaning performance to both heavy-duty powdered detergents and heavy-duty liquid detergents which utilize potassium polyphosphates as the building or sequestering agent.

The term "heavy-duty detergent" as used in the specification and claims refers to a product which is alkaline and is suitable for laundry use. This is contrasted with the term "light-duty detergent", which term refers to a product that has a pH of about 7 and which is suitable for light household cleaning, such as dishes, etc.

The liquid heavy-duty detergent composition of the present invention includes up to about 20%, preferably about 16%, by weight of the total constituents of the composition of a synthetic detergent, having the general formula $R_xR'SO_3HN(R'')_3$ wherein x is a number from 1 to 5, R is selected from alkyl groups having from 1 to 18 carbon atoms, at least one of which has at least 8 carbon atoms, R' is benzene, and R'' is selected from the group consisting of hydrogen, alkyl groups and alkanol groups, said alkyl and alkanol groups containing from 1 to 8 carbon atoms. The synthetic detergent may consist entirely of the above detergent or it may be a mixture consisting of at least 11% by weight of the total constituents in the composition of the above synthetic detergent combined with a sufficient amount to bring the total synthetic detergent percentage to 16% by weight of the total constituents in the composition of a synthetic detergent having the following general formula RCH_2OSO_3R' wherein R is an alkyl group having 10 to 18 carbon atoms and R' is selected from the group of alkali metals, i.e., sodium, potassium, lithium, rubidium, cesium and francium.

In addition to the synthetic detergent, the liquid heavy-duty detergent composition of the present invention includes up to about 20%, preferably about 16%, of sodium

tripolyphosphate as the primary building or sequestering agent, up to about 2%, preferably about 1.5%, SiO_2 as a sodium or potassium silicate as a corrosion inhibitor, up to about 6%, preferably about 5%, of a solubilizing agent, such as an alkali metal aryl sulfonate, as for example, potassium xylene sulfonate or potassium toluene sulfonate, and from 0.25 to 0.5%, preferably about 0.36%, lithium added as a water-soluble lithium compound, as for example, lithium hydroxide monohydrate. In addition, sufficient potassium hydroxide or sodium hydroxide to bring the pH of the solution within the range of 11 to 12.5 is also added, with about 60% water being added to make 100%. If it is desired, about 1% by weight of the total constituents of a soil suspending agent such as potassium carboxy methyl cellulose may also be added as well as minor amounts of an optical bleach, a dye, and a perfume.

It has been found that 0.25 to 0.5% lithium, in the form of a water-soluble lithium compound, such as lithium hydroxide monohydrate, is indispensable in the above formulation, if the formulation is to remain stable and not separate into solid and liquid phases. Although it is not known how the lithium functions in this formulation, nor even what its function is, it has been found that similar results can not be obtained by using sodium or potassium. When equivalent amounts of the corresponding sodium and potassium compounds are substituted for the lithium in the above formulation, the mixture separates almost at once, forming liquid and solid phases. It is only when lithium is present, in the amounts indicated above, i.e., 0.25 to 0.5% by weight of the total composition, that a stable mixture is formed.

Although, as set forth above, the desired amount of lithium may be added to the detergent formulation in the form of any water-soluble lithium compound, it will be understood that the compound used is limited to those compounds, the anion of which will not produce a deleterious effect on either the detergent composition itself, or in any cleaning process in which it is used. Inasmuch as the best laundering results are achieved when the cleaning is done in a solution having a pH between 9 and 10, to achieve this pH, it is desirable that the detergent formulation have an initial pH of between 11 and 12.5. It has been found that this pH may be advantageously reached by adding the lithium in the form of lithium hydroxide monohydrate in the amount of from about 1.5 to 3%, preferably about 2.2%, by weight of the total constituents of the detergent composition.

The major synthetic detergent compounds may be referred to generally as "amine alkyl aryl sulfonates" of which the following are specific examples of these compounds: tetrapropylene benzene triethanolamine sulfonate, tetrapropylene benzene diethanolamine sulfonate, tertiary octyl benzene triethanolamine sulfonate, keryl ($\text{C}_{10}\text{H}_{21}$ to $\text{C}_{14}\text{H}_{29}$) benzene triethanolamine sulfonate, monyl benzene triethanolamine sulfonate, monyl toluene triethanolamine sulfonate, dodecyl toluene triethanolamine sulfonate, dodecyl benzene triethanolamine sulfonate, as well as various other amine derivatives of the above compound, such as for example, the diethaneamine derivatives. Of these compounds, excellent results have been produced when using tetrapropylene benzene triethanolamine sulfonate and keryl benzene triethanolamine sulfonate, and for this reason these compounds are preferred.

The second synthetic detergent compounds may be referred to generally as alkali metal salts of sulfuric acid esters of higher alcohols. Examples of these compounds which are suitable for use in the composition of the present invention are: sodium lauryl sulfate, potassium lauryl sulfate, sodium myristyl sulfate, potassium myristyl sulfate, sodium palmityl sulfate, potassium palmityl sulfate, sodium stearyl sulfate, potassium stearyl sulfate, as well as various other alkali metal salts of the above compounds. Of these compounds, excellent results have

been produced when using sodium or potassium lauryl sulfate and hence, these compounds are preferred in the composition of the present invention.

In forming the liquid detergent composition of this invention, good results have been obtained by mixing the solid ingredients with the aqueous medium with heating where necessary to aid in the dissolving of the solid ingredients. It is understood however, that the ingredients may be combined in any other order which is found to be satisfactory.

In order that those skilled in the art may better understand the compositions of the present invention, the following examples are offered.

Example I

A liquid synthetic detergent formulation is prepared having the following composition in parts by weight:

Alkyl benzene triethanolamine sulfonate ¹ (50% active ingredients, 2% impurities, 48% H_2O)	73.2
Potassium xylene sulfonate (96% active ingredients, 4% H_2O)	9.2
$\text{Na}_2\text{SiO}_3 \cdot 5\text{H}_2\text{O}$	10.6
Sodium tripolyphosphate	35.0
$\text{LiOH} \cdot \text{H}_2\text{O}$	4.0
Potassium carboxy methyl cellulose (5% water solution)	36.0
Water	59.8
Bleach	0.2
Dye (0.75% water solution)	2.0

¹ The alkyl group is a branched carbon chain having about 12 carbon atoms and designated by the manufacturer, The Tennessee Corporation of Atlanta, Georgia, as "Sul-Fon-Ate AAT."

The above composition is liquid having a pH of 12.6 and is stable, there being no layering, i.e., formation of liquid and solid phases, after more than 12 months.

Example II

A synthetic detergent formulation is made having the following composition in parts by weight:

Alkyl benzene triethanolamine sulfonate ¹ (50% active ingredients, 4% impurities, 12% triethanolamine sulfonate and 34% H_2O)	50.18
Potassium xylene sulfonate (96% active ingredients and 4% H_2O)	9.20
Sodium alkyl sulfonate ² (94% active ingredients, 2% fatty alcohols and 4% inorganic salts)	12.30
$\text{Na}_2\text{SiO}_3 \cdot 5\text{H}_2\text{O}$	10.60
Sodium tripolyphosphate	35.00
$\text{LiOH} \cdot \text{H}_2\text{O}$	4.00
Potassium carboxy methyl cellulose (5% water solution)	36.00
Water	70.49
Bleach	0.23
Dye (0.75% water solution)	2.00

¹ The alkyl group is a straight carbon chain containing about 12 carbon atoms and designated by the manufacturer, The National Aniline Division of the Allied Chemical Company, as "Nacconol 60-S."

² The alkyl group is a non-branched chain containing about 12 carbon atoms and designated by the manufacturer, The American Alcolac Corporation, as "Sipex SD."

The above composition is liquid having a pH of 12.3 and is stable, there being no layering, i.e., formation of liquid and solid phases after more than 12 months.

Example III

A synthetic detergent formulation is made having the following composition in parts by weight:

Alkyl benzene triethanolamine sulfonate ¹ (50% active ingredients, 4% impurities, 12% triethanolamine sulfonate and 34% H_2O)	50.18
Potassium xylene sulfonate (96% active ingredients and 4% H_2O)	9.20

¹ Nacconol 60-S.

Example III—Continued

Potassium alkyl sulfonate ² (28% active ingredients, 2% fatty alcohols, 2% inorganic salts and 68% H ₂ O)	50.40
Na ₂ SiO ₃ ·5H ₂ O	10.60
Sodium tripolyphosphate	35.00
LiOH·H ₂ O	4.00
Potassium carboxy methyl cellulose (5% water solution)	36.00
Water	32.39
Bleach	0.23
Dye (0.75% water solution)	2.00

² The alkyl group is a non-branched chain containing about 12 carbon atoms and designated by the manufacturer, The American Alcolac Corporation as "Sipex K."

This composition is liquid, having a pH of 12.4 and exhibits no layering after standing for more than 12 months.

Example IV

A synthetic detergent formulation having the following composition in parts by weight is made:

Alkyl benzene triethanolamine sulfonate ¹ (60% active ingredients, 2% triethanolamine sulfonate, 38% H ₂ O)	61.00
Potassium xylene sulfonate (96% active ingredients, 4% H ₂ O)	9.20
Sodium tripolyphosphate	35.00
LiOH·H ₂ O	6.00
K ₂ SiO ₃ (SiO ₂ :K ₂ O ratio=2.2:1)	17.70
Potassium carboxy methyl cellulose (5% water solution)	36.00
Water	62.87
Bleach	0.23
Dye (0.75% water solution)	2.00

¹ The alkyl group is a branched chain containing about 12 carbon atoms and designated by the manufacturer, The Atlantic Refining Company of Philadelphia, Pennsylvania, as "Ultrawet 60-L."

The above formulation is a liquid having a pH of 12.4 and shows no sign of layering after standing for more than 12 months.

Example V

A synthetic detergent formulation is made up having the following composition in parts by weight:

Alkyl benzene triethanolamine sulfonate ¹ (60% active ingredients, 2% triethanolamine sulfonate, 38% H ₂ O)	61.00
Potassium xylene sulfonate (96% active ingredients, 4% H ₂ O)	9.20
Sodium tripolyphosphate	35.00
Potassium carboxy methyl cellulose (5% water solution)	36.00
LiOH·H ₂ O	5.00
Na ₂ SiO ₃ (SiO ₂ :Na ₂ O ratio=3.3:1)	11.70
Water	69.87
Bleach	0.23
Dye (0.75% water solution)	2.00

¹ Ultrawet 60-L.

The above composition is liquid, having a pH of 11.8 and exhibits no layering after standing for more than 12 months.

Example VI

A synthetic detergent formulation is made up having the following composition in parts by weight:

Alkyl benzene triethanolamine sulfonate ¹ (60% active ingredients, 2% triethanolamine sulfonate, 38% H ₂ O)	61.00
Potassium xylene sulfonate (96% active ingredients, 4% H ₂ O)	9.20
Sodium tripolyphosphate	35.00
Potassium carboxy methyl cellulose (5% water solution)	36.00
LiOH·H ₂ O	4.00

¹ Ultrawet 60-L.

KOH	1.34
Na ₂ SiO ₃ (SiO ₂ :Na ₂ O ratio=3.3:1)	11.70
Water	69.53
Bleach	0.23
Dye (0.75% water solution)	2.00

The above composition is liquid, having a pH of 11.5 and exhibits no layering after standing for more than 12 months.

Example VII

A synthetic detergent formulation is made up as in Example VI except that 3.5 parts by weight LiOH·H₂O, 2.01 parts by weight KOH and 69.36 parts by weight water are used. This formulation is liquid having a pH of 11.4 and exhibits no layering after standing for 12 months.

Example VIII

A synthetic detergent formulation as in Example VI is made up except that 3 parts by weight LiOH·H₂O, 2.68 parts by weight KOH, and 69.19 parts by weight water are used. This formulation has a pH of 11.4, but is very unstable, forming liquid and solid phases upon standing for only one day.

Example IX

A synthetic detergent is made having the following composition in parts by weight:

Alkyl benzene triethanolamine sulfonate ¹ (75% active ingredients, 1% triethanolamine sulfonate, 24% H ₂ O)	49.10
Sodium tripolyphosphate	35.00
Potassium carboxy methyl cellulose (5% water solution)	36.00
Potassium xylene sulfonate (96% active ingredients, 4% H ₂ O)	9.20
K ₂ SiO ₃ (SiO ₂ :K ₂ O ratio=2.2:1)	16.90
KOH	8.00
Water	73.57
Bleach	0.23
Dye (0.75% water solution)	2.00

¹ The alkyl group is a branched hydrocarbon chain containing about 12 carbon atoms and is designated by the manufacturer, Ninol Labs. of Chicago, Illinois as "Ninex 301."

This formulation has a pH of 12.3 but is very unstable, forming solid and liquid layers upon standing overnight.

Example X

A synthetic detergent formulation is made as in Example IX except that 5.7 parts by weight NaOH is used instead of KOH and 75.87 parts by weight water are used. This formulation has a pH of 12.6 and like the formulation of Example VIII is very unstable, separating into solid and liquid layers upon standing overnight.

Example XI

A synthetic detergent formulation is made having the following composition in parts by weight:

Alkyl benzene triethanolamine sulfonate ¹ (60% active ingredients, 2% triethanolamine sulfonate, 38% H ₂ O)	61.00
Sodium tripolyphosphate	35.00
Potassium carboxy methyl cellulose (5% water solution)	36.00
LiOH·H ₂ O	4.00
NaOH	0.95
Potassium xylene sulfonate (96% active ingredients, 4% H ₂ O)	9.20
Na ₂ SiO ₃ (SiO ₂ :Na ₂ O ratio=3.3:1)	11.70
Water	69.92
Bleach	0.23
Dye (0.75% water solution)	2.00

¹ Ultrawet 60-L.

The above formulation has a pH of 12.0 and is very unstable, forming liquid and solid layers upon standing overnight.

From Examples VIII-XI, it can be seen that when less than 0.25% Li, i.e., less than 1.5% $\text{LiOH}\cdot\text{H}_2\text{O}$, is used in the formulations of the present invention, the resulting detergent product is unstable. Moreover, it is also seen that the corresponding sodium and potassium compounds cannot be substituted for the lithium compound in the formulation and still obtain a stable composition.

Example XII

A synthetic detergent formulation is made having the following composition in parts by weight:

Alkyl benzene triethanolamine sulfonate ¹ (60% active ingredients, 2% triethanolamine sulfonate, 38% H_2O)	52.10
Potassium carboxy methyl cellulose (5% water solution)	36.00
Sodium tripolyphosphate	40.30
$\text{LiOH}\cdot\text{H}_2\text{O}$	5.00
Potassium toluene sulfonate (97% active ingredients, 3% H_2O)	9.20
Na_2SiO_3 ($\text{SiO}_2:\text{Na}_2\text{O}$ ratio=3.3:1)	11.70
Water	73.47
Bleach	0.23
Dye (0.75% water solution)	2.00

¹ Ultrawet 60-L.

The above formulation has a pH of 12.2 and is stable, there being no layering after standing for more than 6 months.

Example XIII

A synthetic detergent formulation is made as in Example XII with the exception that 46 parts by weight of sodium tripolyphosphate, 42.6 parts by weight of Ultrawet 60-L and 77.27 parts by weight of water are used. This formulation is a liquid, having a pH of 12.3, and is found to be unlayered after standing for more than 6 months.

To determine the effectiveness of the liquid synthetic heavy-duty detergent formulations of the present invention, washing tests are made comparing the formulation of the present invention with a standard heavy-duty synthetic powder and a synthetic heavy-duty potassium polyphosphate built liquid detergent. The apparatus used in these tests is a Launder-Ometer, the standard laboratory washing machine of the American Association of Textile Chemists and Colorists, manufactured by The Atlas Electric Devices Company of Chicago, Illinois. This machine consists of a water bath, having positioned therein a rotor which carries 20 glass jars or similar sample holders. The rotor is driven in the water bath at a speed of 42 r.p.m., the temperature of the water bath being thermostatically controlled at 120° F.

In making the test, two fabric specimens, impregnated with a standard soil, consisting of lamp black,

wheat starch, and a mixture of vegetable and mineral oils, are placed in each glass jar with 100 ml. of water and 0.5 g.-1 g. of the detergent to be tested, the water having a known hardness. Ten rubber balls are placed in each jar to provide mechanical agitation for the samples and the jars are closed and placed in the Launder-Ometer. The jars are rotated in the Launder-Ometer for a period of 30 minutes at a temperature of 120° F., after which time the fabric specimens are rinsed, by agitation, for 30 seconds in 6 liters of distilled water at a temperature of 110° F. The patches are then placed between two cotton towels and ironed with an electric iron until dry. The amount of light reflected from the patches is measured both before and after the washing test with a standard photometer, the gain in the amount of reflectance after washing being used as the measure of the effectiveness of the detergent. The standard soil used in these tests consists of 3 gms. of Germantown lampblack, 6 gms. of wheat starch and 9 gms. of a vegetable shortening, which materials are warmed to 100° F. and milled into a paste. To this paste is added 12.9 gms. of a high grade, impurity free mineral oil, designated by the manufacturer as Nujol, and the mixture is stirred at a temperature of 100° F. until homogeneous. This mixture is stirred into three liters of carbon tetrachloride and allowed to stand for 2 hours, whereafter Indian Head cotton cloth is impregnated with the mixture. Following the impregnation, cloth is dried and 2" x 2½" rectangular swatches are cut from the cloth, which swatches are used in the above-described test.

The results of these washing tests are shown in the following example. It is to be noted in the example that the heavy-duty powder synthetic detergent which is used is a commercial product containing about 20% of a synthetic detergent which is a combination of a sodium alkyl aryl sulfonate and a sodium alcohol sulfate about 2% of a condensed alkanol amide of a fatty acid as a foam stabilizer, about 45% of sodium tripolyphosphate as the alkaline builder, about 7% of sodium metasilicate as the corrosion inhibitor, about 18% of sodium sulfate to increase the bulk of the product, about 1% sodium carboxy methyl cellulose as the soil suspending agent and the remainder (about 7%) water.

The synthetic heavy-duty liquid detergent used is, likewise, a commercial product containing about 10% of potassium alkyl aryl sulfonate as the synthetic detergent, about 7% of a condensed alkanol amide of a fatty acid as the foam stabilizer, about 20% of tetrapotassium pyrophosphate as the alkaline builder, about 7.5% sodium xylene sulfonate as the solubilizing agent, about 12% liquid potassium silicate (30% solution) as the corrosion inhibitor, about 3% potassium hydroxide, about 1% sodium carboxy methyl cellulose as the soil suspending agent, and the remainder (about 40%) water.

Example XIV

	Detergent Conc. (Name of Detergent on 100 ml. H_2O)	H_2O Hardness (p.p.m. of CaCO_3)	Soiled Cloth Reflectance	Washed Cloth Reflectance	Gain
Heavy Duty Powder-----	0.5	Distilled H_2O -----	38.3	76.5	38.2
K Built Liquid-----	0.5	Distilled H_2O -----	38.3	71.2	32.9
Example II-----	0.5	Distilled H_2O -----	31.0	68.0	36.4
Heavy Duty Powder-----	0.5	50-----	35.5	78.0	42.5
K Built Liquid-----	0.5	50-----	32.6	71.9	38.3
Example II-----	0.5	50-----	33.5	66.0	32.5
Example II-----	0.7	50-----	36.5	74.3	37.8
Heavy Duty Powder-----	0.5	150-----	37.5	75.3	37.8
K Built Liquid-----	0.5	150-----	35.6	67.8	32.2
Example III-----	0.5	150-----	34.4	67.8	33.4
Heavy Duty Powder-----	0.5	300-----	39.7	74.7	35.0
K Built Liquid-----	0.5	300-----	40.4	68.8	28.4
Example II-----	0.5	300-----	36.5	58.7	22.2
Example II-----	0.7	300-----	39.5	70.9	31.4

From the above example, it can be seen that when equal quantities, by weight, of the detergent formulations are used, the synthetic liquid heavy-duty detergents of the present invention are at least comparable in washing effectiveness to the heavy-duty powder and the potassium built heavy-duty liquid. It must be noted however, that the formulations of the present invention contain only about 40% active ingredients as compared to the potassium built liquid which contains 50% active ingredients or the heavy-duty powder which contains almost 100% active ingredients. It can thus be seen that when quantities of the detergents are used containing equivalent amounts of active ingredients, i.e., .7 gm. of the formulation of the present invention and .5 gm. of the potassium built liquid, the washing effectiveness of the formulation of the present invention are equal to or better than that of the potassium built liquid. Likewise, for the heavy-duty powder, it would be necessary to use better than 1 gm. of the present formulation to have active ingredients equivalent to those in a half a gram of a heavy-duty powder and similar washing effectiveness would result.

While there have been described various embodiments of the invention, the methods and products described are not intended to be understood as limiting the scope of the invention as it is realized that changes therewithin are possible and it is further intended that each element recited in any of the following claims is to be understood as referring to all equivalent elements for accomplishing substantially the same results in substantially the same or equivalent manner, it being intended to cover the invention broadly in whatever form its principle may be utilized.

What is claimed is:

1. A stable heavy-duty liquid synthetic detergent composition comprising 11% to 20% of a synthetic detergent, at least 11% of which is an amine alkyl aryl sulfonate having the general formula:

where x is a number from 1 to 5, R is selected from alkyl groups having 1 to 18 carbon atoms, at least one of which has at least 8 carbon atoms, R' is benzene, and R'' is selected from the group consisting of hydrogen, alkyl groups and alkanol groups, said alkyl and alkanol groups containing from 1 to 8 carbon atoms, and up to 5% of which is an alkali metal salt of a sulfuric acid ester of a higher alcohol, 15% to 20% of sodium tripolyphosphate as the alkaline builder, 1% to 2% of SiO_2 as an alkali metal silicate as the corrosion inhibitor, 4% to 6% of an alkali metal aryl sulfonate, the aryl group of which is selected from the group consisting of xylene and toluene, as the solubilizing agent, and in addition to said alkali metal silicate, from 0.25 to 0.5% lithium as a lithium hydroxide, up to about 1% of potassium carboxy methyl cellulose as the soil suspending agent, the remainder of said composition being water, all of said percentages being percent by weight of the total constituents of the composition.

2. The stable heavy-duty liquid synthetic detergent composition as defined in claim 1 wherein the alkyl aryl amine sulfonate is tetrapropylene benzene triethanolamine sulfonate, the alkali metal salt of the sulfuric acid ester of a higher alcohol is sodium lauryl sulfate, the alkali metal silicate is sodium metasilicate, the alkali metal aryl sulfonate is potassium xylene sulfonate, and the lithium hydroxide is lithium hydroxide monohydrate.

3. A stable heavy duty liquid synthetic detergent formulation having the following composition in percent by weight:

Percent	
Tetrapropylenebenzene triethanolamine sulfonate	15.9
Potassium xylene sulfonate	4.0
Sodium tripolyphosphate	15.2
Lithium hydroxide monohydrate	2.6
Potassium liquid silicate having an $SiO_2:K_2O$ ratio	

Percent	
of 2.2:1 as a 28.4% solution	7.3
Potassium carboxy methyl cellulose	0.8
Water	Remainder

5 4. A stable heavy-duty liquid synthetic detergent formulation having the following composition in percent by weight:

Percent	
Keryl benzene triethanolamine sulfonate	10.9
Sodium lauryl sulfate	5.0
Sodium metasilicate	4.6
Lithium hydroxide monohydrate	1.7
Sodium tripolyphosphate	15.2
Potassium xylene sulfonate	4.0
Potassium carboxy methyl cellulose	0.8
Water	Remainder

10 5. A stable heavy-duty liquid synthetic detergent formulation having the following composition in percent by weight:

Percent	
Tetrapropylene benzene triethanolamine sulfonate	15.9
Sodium tripolyphosphate	15.2
Potassium xylene sulfonate	4.0
Lithium hydroxide monohydrate	1.7
Sodium metasilicate	4.6
Potassium carboxy methyl cellulose	0.8
Water	Remainder

15 6. A stable heavy-duty liquid synthetic detergent formulation having the following composition in percent by weight:

Percent	
Keryl benzene triethanolamine sulfonate	10.9
Potassium lauryl sulfate	5.0
Potassium xylene sulfonate	4.0
Sodium tripolyphosphate	15.2
Sodium metasilicate	4.6
Lithium hydroxide monohydrate	1.7
Potassium carboxy methyl cellulose	0.8
Water	Remainder

20 7. A stable heavy-duty liquid synthetic detergent formulation having the following composition in percent by weight:

Percent	
Tetrapropylenebenzene triethanolamine sulfonate	15.9
Sodium tripolyphosphate	15.2
Potassium xylene sulfonate	4.0
Sodium liquid silicate having an $SiO_2:Na_2O$ ratio of 3.3:1 as a 38.0% solution	5.1
Lithium hydroxide monohydrate	1.7
KOH	0.6
Potassium carboxy methyl cellulose	0.8
Water	Remainder

25 8. A stable heavy-duty liquid synthetic detergent formulation having the following composition in percent by weight:

Percent	
Tetrapropylenebenzene triethanolamine sulfonate	15.9
Sodium tripolyphosphate	15.2
Potassium xylene sulfonate	4.0
Sodium liquid silicate having an $SiO_2:Na_2O$ ratio of 3.3:1 as a 38.0% solution	5.1
Lithium hydroxide monohydrate	1.5
KOH	0.9
Potassium carboxy methyl cellulose	0.8
Water	Remainder

30 9. A stable heavy-duty liquid synthetic detergent formulation having the following composition in percent by weight:

Percent	
Tetrapropylenebenzene triethanolamine sulfonate	13.6
Sodium tripolyphosphate	17.5
Potassium toluene sulfonate	4.0

	Percent
Sodium liquid silicate having an SiO ₂ :Na ₂ O ratio of 3.3:1 as a 38.0% solution	5.1
Lithium hydroxide monohydrate	2.2
Potassium carboxy methyl cellulose	0.8
Water	Remainder

10. A stable heavy-duty liquid synthetic detergent formulation having the following composition in percent by weight:

	Percent
Tetrapropylenebenzene triethanolamine sulfonate	11.1
Sodium tripolyphosphate	20.0
Potassium toluene sulfonate	4.0
Sodium liquid silicate having an SiO ₂ :Na ₂ O ratio of 3.3:1 as a 38.0% solution	5.1
Lithium hydroxide monohydrate	2.2
Potassium carboxy methyl cellulose	0.8
Water	Remainder

11. A stable heavy-duty liquid synthetic detergent formulation having the following composition in percent by weight:

	Percent
Tetrapropylenebenzene triethanolamine sulfonate	15.9
Sodium tripolyphosphate	15.2
Potassium xylene sulfonate	4.0
Lithium hydroxide monohydrate	2.2
Potassium carboxy methyl cellulose	0.8
Sodium liquid silicate having an SiO ₂ :Na ₂ O ratio of 3.3:1 as a 38.0% solution	5.1
Water	Remainder
